AUTOMATIC RECLOSED CIRCUIT
BREAKER SYSTEM

E. Vernon Ellett, Pocahontas, Va., assignor to
Westinghouse Electric & Manufacturing Com-
pany, East Pittsburgh, Pa., a corporation of
Pennsylvania

Application March 11, 1933, Serial No. 660,378

14 Claims. (Cl. 175—294)

My invention relates, generally, to circuit breaker systems, and more particularly to automatic reclosing circuit breaker systems.

The object of my invention generally stated is 5 to provide an automatic reclosing circuit interrupter system which shall be simple and effective in operation and which may be economically manufactured and installed.

A more specific object of my invention is to provide 10 for automatically reclosing a circuit interrupter, which opens in response to abnormal or predetermined circuit conditions, in accordance with a predetermined sequence, the circuit interrupter being automatically locked out against 15 further automatic reclosures in the event it does not remain closed for a predetermined time following the last reclosure of the sequence.

Another object of my invention is to provide an 20 automatic reclosing circuit breaker system which shall function automatically in response to the opening of the breaker to effect a substantially instantaneous reclosure of the breaker followed by a predetermined number of timed reclosures, the reclosing system being rendered ineffective to 25 provide further instantaneous reclosures after the first reclosure and again rendered effective to produce such a reclosure in the event that the breaker remains closed for a predetermined time interval after any reclosure.

30 A further object of my invention is to provide for effecting a substantially instantaneous reclosure of a circuit interrupter in response to the automatic opening of the interrupter and for preventing a second instantaneous reclosure of 35 the circuit interrupter unless the interrupter remains closed for a predetermined interval of time.

A still further object of my invention is to provide 40 an automatic reclosing circuit breaker system which shall function automatically to effect a substantially instantaneous reclosure of the breaker in response to the opening thereof, and for thereafter effecting a timed reclosure or to 45 effect a second instantaneous reclosure dependent upon the breaker remaining in the reclosed position for a predetermined interval of time.

Another object of my invention is to provide an 50 automatic reclosing circuit breaker system which may be constructed of simple and inexpensive relays only and which will provide a high degree of reliability with low first cost and maintenance expense to the user.

In practicing my invention in its preferred 55 form, a control relay is used for controlling the operation of the closing device of the breaker which may be in the form of a solenoid, motor or

otherwise. The control relay is controlled principally by auxiliary switches or limit switches on the breaker and by means of two lock-out relays.

The normal operating position of the reclosing system is such that the lock-out relays are in their reset positions which renders the control relay responsive to an opening of the breaker on overload, or other circuit disturbance to effect an initial reclosure of the breaker substantially instantaneously. The operation of the 10 control relay also operates a lock-out relay to its lock-out or open position, thereby rendering the control relay unresponsive to a reopening of the breaker.

If the breaker reopens, a timing relay is set 15 into operation and at the expiration of a desired time interval operates a relay which closes to energize the control relay and also to operate the second lock-out relay to its lock-out or open position, to render the timing means ineffective 20 to again reclose the breaker.

In the event that the breaker reopens following the second reclosure the reclosing system is 25 ineffective to effect another reclosure and the breaker is, therefore, locked out of service until attended by an operator.

When the breaker is reclosed on the last reclosure, a second timing means is set into operation and if the breaker remains closed for a desired time, as determined by the setting of 30 this relay, it operates both of the lock-out relays to their reset or normal positions, thereby rendering the system responsive to a subsequent opening of the breaker.

Referring to the single figure of the drawing, 35 the reference character 10 designates generally a circuit breaker connected between a source of power represented by conductors 11 and a load circuit 12. The circuit breaker may be provided with any type of closing device, such for example, as an ordinary solenoid 13, as shown. The breaker may also be provided with a tripping device 14 comprising a spring-biased latch 15 which is disposed to be operated by a solenoid 16 in response to some predetermined abnormal 45 condition in the load circuit, and in this instance, is connected to the load circuit by means of the current transformer 17.

Current for operating the reclosing system may be obtained from the power circuit 11 by means 50 of a suitable transformer 18, having one end of its secondary winding connected directly to the control conductor X and the opposite end connected to control conductor Y through a suitable switch 19.

In this embodiment of the invention, the energization of the closing solenoid 13 is controlled by means of a control relay 21, which is controlled in such manner as to effect a predetermined sequence of reclosing operations, as will be described more fully hereinafter.

5 In order to provide for deenergizing the control relay 21 after the breaker has been closed, there is provided a cut-off relay 22 which is controlled by the breaker in such manner as to deenergize control relay 21, and thereby deenergize the closing solenoid of the breaker.

10 Since it is desired to effect the first reclosure of the breaker substantially instantaneously, and thereafter produce a timed reclosure, provision is made for preventing a second instantaneous reclosure by means of a lock-out relay 23, which, when operated to its lock-out position, renders the control relay 21 unresponsive to a second 15 opening of the breaker until the timing devices function. Any suitable type of lock-out relay may be used, such for example, as a toggle relay, as shown, having an opening or lock-out coil 24 and a reset coil 25.

20 25 The timing for the second reclosure of the breaker may be effected by means of any suitable timing device, such for example, as an induction relay 26, as shown. Since the construction of relays of this type is well known, it has been 30 deemed unnecessary to describe this relay in detail other than to state that it is provided with the usual rotating disc element 27, carrying a movable contact member 28 which is disposed to be actuated into engagement with stationary 35 contact members 29, a damping magnet 31 and an operating electromagnet 32. The movable contact member is held in the open position when the relay is deenergized by means of a suitable coil spring 33.

40 45 In order to provide the feature of rendering the reclosing system ineffective to produce a reclosure of the breaker following the last reclosure of the predetermined sequence or cycle, a second lock-out relay 34, of the toggle type, is utilized. This relay may be of the same general construction as the lock-out relay 23, having a lock-out coil 35 and a reset coil 36. As will be described more 50 fully hereinafter, the lock-out relay 34 is operated simultaneously with the second reclosure of the breaker and functions to render the reclosing system temporarily inoperative to effect a further reclosure in the event the breaker opens immediately.

55 60 The additional feature of the system of rendering the system effective following a lock-out operation in the event that the circuit breaker remains closed for a predetermined time is provided by means of a second time-delay relay 37, which may be identical in construction to the relay 26, previously described. The circuit breaker 10 may be operated to the closed position initially by means of a push-button switch 38, which, upon being closed, establishes an energizing circuit for the control relay 21. This circuit extends 65 from conductor X through conductors 65 and 39, switch 38, coil of relay 21, and normally-closed contact members 41 of the cut-off relay 22 to conductor Y.

70 75 Upon the operation of control relay 21 an energizing circuit for the closing solenoid 13 is established which extends from conductor X, through the conductor 42, solenoid 13, conductors 43 and 44 and contact members 45 of relay 21 to conductor Y. The operation of the control relay also establishes its own holding circuit which ex-

tends from energized conductor 39 through contact members 46 and conductor 47 to one end of the coil, as shown.

75 In order to operate the cut-off relay 22 in response to the closure of the breaker and thereby deenergize the control relay 21 and solenoid 13, the breaker is provided with the limit switch 48 which, when closed, establishes an energizing circuit extending from conductor Y through switch 48, conductor 49, coil of relay 22, closed contact members 46 of the control relay 21 and conductors 65 and 39 to conductor Y. The operation of the cut-off relay interrupts the holding circuit for the control relay which, in turn, opens its contact members 46 to deenergize the cut-off 15 relay 22.

10 15 Assuming now that the breaker opens in response to an abnormal condition in the load circuit, a substantially instantaneous first reclosure is effected by rendering the control relay 21 initially responsive to the opening operation of the breaker.

20 25 As will be observed, the breaker is provided with a second limit switch 51 which closes when the breaker is in the open position to establish an energizing circuit for the control relay, which circuit extends from conductor X through conductors 42 and 52, contact members 53 of the lock-out relay 23 which is now in its normal or reset position, conductor 54, limit switch 51, conductor 55, coil of control relay 21, and contact members 41 of the cut-off relay 22 to conductor Y. The control relay 21 is thus operated to effect the energization of the closing solenoid 13 followed by the operation of the cut-off relay 22, as described hereinbefore.

30 35 In addition to this function, the control relay 21 establishes an energizing circuit for the lock-out relay 23 to effect the operation of this relay to the lock-out position, thereby to prevent a second instantaneous reclosure and to prevent any attempted reclosure in the event that the control voltage is lost for any reason. The energizing circuit thus established for the lock-out coil 24 of the lock-out relay extends from conductor 45 Y through contact members 45 of control relay 21, conductor 44 and coil 24 to conductor X. It is thus apparent that when contact members 53 of the lock-out relay 23 are opened the previously described energizing circuit for the control 50 relay 21 is interrupted and consequently the relay does not respond to the closure of the limit switch 51.

40 45 In the event that the breaker reopens immediately, so that a second reclosure is necessary, 55 provision is made for initiating the operation of the timing relay 26 in response to the reopening of the breaker. In this instance, this is accomplished by means of a third limit switch 56 on the breaker which, when closed, establishes a circuit 60 extending from conductor Y through conductor 57, opening electro-magnet 32, limit switch 56, conductor 58, contact members 59 of lock-out relay 34 and conductors 61 and 65 to conductor X. As will be readily understood the timing relay 26 may be adjusted to close its contact members at the expiration of any desired time interval.

55 60 Upon the expiration of this time interval contact members 29 of the timing relay 26 are bridged by the moving contact member 28 to establish an operating circuit for an auxiliary relay 62. This circuit extends from conductor X through conductors 42, 52 and 63, contact mem- 75

bers 29, conductor 64, and coil of relay 62, to conductor Y.

In response to the operation of the auxiliary relay 62 a second energizing circuit for the control relay 21 is established. This circuit now extends from conductor X through conductors 65 and 61, contact members 66 of the lock-out relay 34, contact members 67 of auxiliary relay 62, conductor 68 which connects with the conductor 54, and limit switch 51 to the coil of control relay 21, as previously described. The closure of control relay 21 now effects the second reclosure of the breaker which occurs at a predetermined time interval following the reopening 15 on the first reclosure.

In order to produce a temporary lock-out condition of the reclosing system following the second reclosure, provision is made for effecting the operation of the second lock-out relay 34 to 20 its lock-out position simultaneously with the second reclosure of the breaker. This is accomplished in this instance by means of a second contact member 69 on the auxiliary relay 62 which closes to energize the lock-out coil 35 over 25 a circuit extending from conductor X to coil 35, contact members 69, conductors 71 and 44 and contact members 45 of the control relay 21 to conductor Y.

It will now be observed that the energizing 30 circuit for the control relay 21 has been interrupted at contact members 53 of the lock-out relay 23, and also at contact members 66 of the lock-out relay 34, thereby making it impossible to effect either an instantaneous or a timed 35 reclosure.

It is desirable, however, to provide for resetting the system whereby it will again respond automatically to provide a second sequence of reclosing operations, in the event that the 40 breaker remains closed for a predetermined time following the time reclosure. In order to effect this function, the second timing relay 37 is rendered responsive to the closure of the breaker by means of a fourth limit switch 72, the operation 45 of the timing relay 37 being dependent upon either one of the lock-out relays 23 and 34 being in their lock-out position.

As shown, contact members 73 of lock-out relay 23 and contact members 74 of lock-out relay 34 50 are connected in parallel to conductor X and through conductor 75, limit switch 72, conductor 76 and electro-magnet 77 of the timing relay 37 to conductor Y. It is thus apparent that should the circuit breaker have remained closed 55 following the first reclosure and the lock-out relay 23 only been operated, this energizing circuit for the timing relay 37 would have been established and the timing relay operated to reset the system. Likewise, if both of the lock-out 60 relays had been operated, such as was previously described, the timing relay 37 would have also been operated to reset the system from the lock-out position.

When the moving contact member 78 of the timing relay 37 bridges contact members 79, a 65 circuit is established from conductor X which may extend through either contact members 73 of lock-out relay 23 or contact members 74 of lock-out relay 34 to conductor 75 and through conductor 81, contact members 79 and through the reset coils 38 and 25 of the lock-out relays which are connected in parallel, as shown, and conductor 82 to conductor Y. This effects the 70 operation of these relays to their original or reset 75

position, thereby rendering the system responsive to a subsequent reopening of the breaker.

In view of the foregoing, it will be apparent that I have provided a novel reclosing system comprised of relays only, thereby making it economical to construct, and which operates in a reliable manner to produce a predetermined sequence of reclosures. 5

It may be stated in conclusion, that, while the illustrated example constitutes a material embodiment of my invention, I do not wish to limit myself strictly to the exact details herein illustrated, since modifications of the same may be made without departing from the spirit of the invention, as defined in the appended claims. 15

I claim as my invention:

1. In an automatic reclosing circuit breaker system, in combination, a circuit breaker, means for automatically opening the breaker, closing means for the breaker, means independent of the opening means responsive to the opening of the breaker for causing the closing means to reclose the breaker substantially instantaneously, means responsive to the operation of the reclosing means for rendering the reclosing means ineffective to 20 produce a second instantaneous reclosure, timing means operable in response to a reopening of the breaker for causing the closing means to effect a second reclosure of the breaker at the expiration of a predetermined interval, means 30 responsive to the operation of the timing means for rendering said timing means ineffective to operate the closing means, and additional timing means operable in response to the breaker remaining closed a predetermined time after any 35 reclosure for rendering the reclosing means again effective to produce a substantially instantaneous reclosure.

2. In an automatic reclosing circuit breaker system, in combination, a circuit breaker, means for automatically opening the breaker, closing means for the breaker, means independent of the opening means responsive to the opening of the breaker for causing the closing means to reclose the breaker substantially instantaneously, said 45 means being disposed to become unresponsive to an immediate reopening of the breaker, timing means operable in response to a reopening of the breaker for causing the closing means to effect a second reclosure of the breaker at the expiration of a predetermined interval, said means being disposed to become unresponsive to an immediate reopening of the breaker, and additional timing means dependent upon the breaker remaining in the reclosed position for a predetermined time after either the first or second reclosure thereof for rendering both the said means for effecting a substantially instantaneous reclosure and the timing means again responsive to the opening of the breaker. 50

3. In an automatic reclosing circuit breaker system, in combination, a circuit breaker, means for automatically opening the breaker, closing means for the breaker, means including a control relay responsive to the initial opening of the 65 breaker for energizing the closing means to effect a substantially instantaneous reclosure of the breaker, means controlled by said control relay whereby the means including the control relay is rendered unresponsive to a reopening of the breaker, time-delay means responsive to the reopening of the breaker for effecting the operation of the control relay to reclose the breaker at the expiration of a predetermined time interval, means responsive to the operation of the time- 70 75

- delay means for rendering said time-delay means ineffective to again reclose the breaker, and a second time delay means operable to render said means including the control relay and the first-
 5 mentioned time-delay means responsive to further reopening operations of the breaker, said time delay means being dependent for its functioning on the breaker remaining closed for a predetermined time interval.
- 10 4. The combination with a power supply circuit, a load circuit and a circuit interrupter therebetween, of means for automatically opening the interrupter in response to an abnormal condition of the load circuit, control means responsive to the opening of the interrupter for effecting a substantially instantaneous reclosure thereof, means responsive to the operation of the control means operable to cause said control means to effect a second substantially instantaneous reclosure of the interrupter dependent upon the interrupter remaining closed until the expiration of a predetermined time interval following said first instantaneous reclosure, and means operable to cause said control means to effect a timed reclosure in the event the breaker opens before the expiration of said predetermined time interval.
- 15 5. The combination with a power supply circuit, a load circuit and a circuit interrupter therebetween, of means for automatically opening the interrupter in response to an abnormal condition of the load circuit and means responsive to the opening of the interrupter for effecting a sequence of reclosing operations thereof in the event the interrupter continues to reopen, the first of said reclosures being effected substantially instantaneously, said means including means operable to render the system operable to effect a second sequence of reclosures in the event that the interrupter remains closed for a predetermined time following the last reclosure of the first sequence of reclosures.
- 20 6. In combination, a circuit interrupter, means for opening the interrupter in response to predetermined conditions, means including a control relay responsive to the opening of the interrupter for effecting a substantially instantaneous reclosure thereof, lock-out means responsive to the operation of said control relay for rendering said control relay ineffective to reclose the interrupter in response to a second opening thereof, time-delay means responsive to the opening of the interrupter for operating the control relay at the expiration of a predetermined time interval to reclose the interrupter a second time, and additional time-relay means responsive to an opening operation of the interrupter for operating the lock-out means to again render the means including the control relay effective to reclose the interrupter substantially instantaneously, dependent upon the interrupter remaining closed for a predetermined time interval following any reclosure thereof.
- 25 7. In combination, a circuit breaker, means for opening the breaker, means including a control relay responsive to an initial opening of the breaker for effecting a single substantially instantaneous reclosure thereof, and means including a plurality of timing relays responsive to the position of the breaker for effecting a timed reclosure of the breaker in the event that it re-opens within a predetermined time interval following the substantially instantaneous reclosure and for rendering the means including the control relay operable to effect another substantially instantaneous reclosure in the event that the breaker remains closed for a predetermined time interval following either a substantially instantaneous reclosure or a timed reclosure.
- 30 8. In combination, a circuit interrupter, means for opening the interrupter in response to predetermined conditions, means operable to close the interrupter, and reclosing means responsive to the opening of the interrupter for effecting a sequence of reclosures including a substantially instantaneous reclosure thereof followed by a predetermined number of timed reclosures in the event the interrupter continues to reopen, said means including a timing means for controlling the timed reclosures, and lock-out means controlled by the timing means for rendering said timing means inoperative to reclose the interrupter, and a second timing means operable in response to the interrupter remaining closed a predetermined time to effect the operation of the lockout means to again render said reclosing means automatically operable to repeat the sequence of reclosures in response to an opening of the interrupter.
- 35 9. In an automatic reclosing circuit breaker system, in combination, a circuit breaker provided with closing means, means for automatically opening the breaker, a control relay for controlling the energization of the closing means, an energizing circuit for the control relay, switch means dependent upon the opening of the breaker for closing said energizing circuit to operate the control relay and reclose the breaker, means controlled by the control relay to interrupt said energizing circuit, thereby rendering the switch means ineffective to cause a second reclosure of the breaker, timing means responsive to the re-opening of the breaker for again completing an energizing circuit for the control relay to reclose the breaker at the expiration of a predetermined time interval, and means responsive to the operation of the timing means for rendering said timing means further ineffective to reclose the breaker.
- 40 10. In an automatic reclosing circuit breaker system, in combination, a circuit breaker provided with closing means, means for automatically opening the breaker, a control relay for controlling the energization of the closing means, an energizing circuit for the control relay, switch means dependent upon the opening of the breaker for closing said energizing circuit to operate the control relay and reclose the breaker, means controlled by the control relay to interrupt said energizing circuit, thereby rendering the switch means ineffective to cause a second reclosure of the breaker, timing means responsive to the re-opening of the breaker for again completing an energizing circuit for the control relay to reclose the breaker at the expiration of a predetermined time interval, and means responsive to the operation of the timing means for rendering said timing means further ineffective to reclose the breaker.
- 45 11. In combination, a circuit breaker, means for opening the breaker in response to predetermined conditions, closing means for the breaker, a control relay for controlling the closing means, switch means responsive to the opening of the breaker for energizing the control relay to ef-

- fect a substantially instantaneous reclosure thereof, a lock-out relay controlled by the control relay for rendering said control relay unresponsive to the switch means in the event that 5 the breaker reopens, a timing relay responsive to the opening of the breaker for effecting the operation of the control relay to reclose the breaker at the expiration of a predetermined time interval, a second lock-out relay controlled 10 by the timing relay for rendering said timing relay unresponsive to a reopening of the breaker, and means responsive to the breaker remaining in the closed position for a predetermined time after any reclosure for controlling the lock-out 15 relays to render the control relay and the timing relay effective to produce further reclosures.
12. In combination, a circuit breaker, means for opening the breaker, means including a control relay responsive to the opening of the breaker 20 for effecting an immediate reclosure thereof, said means becoming unresponsive to an immediate reopening of the breaker, means including said control relay responsive to the reopening of the breaker for effecting a second reclosure thereof 25 after a predetermined time interval, said means becoming unresponsive to an immediate reopening of the breaker, and time-delay means operable dependent upon the breaker remaining reclosed for a predetermined time following either the 30 immediate reclosure or the timed reclosure for rendering either the first or second means including the control relay, or both, again responsive to the opening of the breaker.
13. In an automatic reclosing circuit breaker
- system, in combination, a circuit breaker, means for automatically opening the breaker, means independent of the opening, means responsive to the opening of the breaker for effecting a substantially instantaneous first reclosure thereof, time-delay means dependent for its operation upon the reopening of the breaker for operating the reclosing means to effect a second reclosure thereof at the expiration of a predetermined time interval, and means responsive to the operation 10 of the time-delay means for rendering said time-delay means ineffective to again reclose the breaker in the event that the breaker immediately reopens following said second reclosure.
14. In an automatic reclosing circuit breaker 15 system, in combination, a circuit breaker, means for automatically opening the breaker, control means independent of the opening means and operable in response to the opening of the breaker for effecting a substantially instantaneous re- 20 closure thereof, means responsive to the operation of said control means for rendering it unresponsive to an immediate reopening of the breaker, time-delay means dependent for its operation upon the breaker remaining closed for a predetermined time interval following the substantially 25 instantaneous reclosure for again rendering the control means operable to effect another substantially instantaneous reclosure, and additional time-delay means operable in the event that the 30 breaker reopens before the expiration of said predetermined time interval to cause said control means to effect a timed reclosure of the breaker.

E. VERNON ELLETT.
